UNITED STATES PATENT OFFICE.

WILLIAM H. APPLEMAN, OF OLEAN, NEW YORK.

SAWMILL LOG-SETTING DEVICE.

1,241,807.

Specification of Letters Patent.

Patented Oct. 2, 1917.

Application filed April 16, 1915. Serial No. 21,909.

To all whom it may concern:

Be it known that I, WILLIAM H. APPLEMAN, a citizen of the United States, and a resident of Olean, in the county of Cattaraugus and State of New York, have invented 5 a new and useful Improvement in Sawmill Log-Setting Devices, of which the following is a specification.

My invention relates especially to accurate 10 means for actuating and controlling the movement of what is termed the rocker shaft of such log setting devices, in order to impart proper movement to that portion of the setting mechanism that engages more 15 directly with the setting shaft and head blocks.

The object of my invention is to provide 20 a means for securing greater accuracy in moving the head block knees or standards toward the saw line, greater accessibility to 25 working parts and at the same time eliminate the impact and objectionable inertia found in other machines for a like purpose.

I attain these objects in the mechanism 30 illustrated in the accompanying drawing in which—

Figure 1 is a left side elevation view of my device, assembled complete in connection with the usual type of carriage used in a 35 large modern sawmill.

Fig. 2 presents side elevations and an end view of members of Fig. 1, which will be later referred to in detail.

Fig. 3 is a plan view of my device shown 40 in connection with portions of a sawmill head block, and in which the usual type of setting mechanism is fairly illustrated.

Fig. 4 is a right side elevation view of my device assembled and as usually applied to 45 a sawmill carriage and in which the usual type of setting mechanism is further illustrated.

Fig. 5 is a longitudinal sectional view of the cylinder, valve chest and valve of my 50 device, and in which the port arrangement and piston control is illustrated.

Fig. 6 is a transverse section taken on a line *a—a* of Fig. 5.

Fig. 7 is a longitudinal section of a vapor 55 employing cylinder, piston, and valve, which are herewith presented for the purpose of illustration and comparison, and therefore form no real part of my own device.

Like characters indicate like parts 60 throughout the various figures.

A carriage frame 1 is illustrated for showing the general application of my device.

It is mounted on a series of trucks 2 and resting on the carriage, is a head block 3, two or more of which are invariably used, 60 each being fitted with a knee or standard 4, said standards being fitted to said blocks with a tongue and groove engagement, and carrying on their lower surface a rack 5, which in turn engages with a pinion 6, 65 which is actuated by a setting shaft 7, and which extends through and connects any number of blocks that may be employed.

My improvement proper consists of a 70 motor comprising a steam or vapor using engine, having a cylinder 8 which preferably is cast integral with the bed or frame shown in connection therewith, and which not only aids in supporting other important mechanism entering into my device, but also 75 aids in providing means for supporting my device in its relation to said carriage and blocks. In said cylinder 8, a working or vapor actuated piston 9 is fitted having a piston rod 10 which extends outward through a stuffing box 11. Attached to cylinder 8 is a valve chest 12, containing a valve 13 having an extending valve rod 14, with means of connection with an operating lever 15, and by means of which vapor is 80 alternately admitted and expelled from said cylinder 8. Located at the right side of cylinder 8 is the usual type of setting mechanism, comprising a pair of wheels 16 and 17,—usually termed ratchet wheels, said 85 wheels being rigidly attached to setting shaft 7, and being actuated by what are usually termed pawl carriers 18 and 19. Wheels 16 and 17 may be either smooth 90 faced, or may be provided with teeth, and said pawl carriers may be fitted with any form of gripping device, which engages while moving in one direction and releases while moving in the opposite direction.

Lying parallel with setting shaft 7 and 95 reasonably adjacent to said wheels 16 and 17 and the pawl carriers 18 and 19 is a shaft 20, usually termed the rocker shaft of the setting mechanism, said shaft being pivotally supported near one end by the bed or frame of cylinder 8, and at its opposite end by a tie box frame piece 21. Rigidly attached to said shaft is a rocker having oppositely disposed forked arms 23 and 24, 100 and pivotally attached to arm 23 is a con-

105

110

necting rod 25 which is also pivotally attached to pawl carrier 18, while a similar rod 26 is pivotally attached to arm 24 and also to pawl carrier 19. Lying on each side of, and parallel with the setting shaft 7, are shafts 27 and 28, which operate in connection with a receding mechanism not shown, and therefore it and said shafts are not involved in or made a part of my application. 5 Rigidly attached to the left end of shaft 20 is an arm 29, which at its outer end is provided with a crank pin 30, and adjacent to shaft 20, and pivotally mounted in the frame of cylinder 8 is a shaft 31, which carries a rigidly attached arm 32. Rigidly attached to shaft 31, is also a long swinging lever 33, generally known as a graduating or setting lever, the upper end of which is adapted to engage with a radial quadrant 10 34 by means of a latch 35 which fits into one or more of a series of notches which extend over the entire length of said quadrant. At the extreme outer end of the bed of cylinder 8 is pivotally mounted a shaft 36, and 15 rigidly attached to said shaft, is an arm or rocker 37, which in turn is provided with a curved guide 38. Pivotally attached to piston rod 10 by a bolt or pin 39 is a connecting rod 40, the outer end of which is pivotally attached to arm 37 by bolt or pin 30. Located on arm 37 and having a sliding tongue and grooved fit in radial guide 38 is a curved block 42, said block is provided with pivotal openings into which are 20 inserted pivotal bolts 43 and 44. Attached to pivotal bolt 44 is a link 45 which extends to, and is pivotally attached to arm 32 by a bolt 46, and attached to block 42 by pivotal bolt 43 is a link 47 which is pivotally attached to crank pin 30 of arm 29. Preferably arm 37 is so located as to cause guide 38 to lie in a true concentric relation to crank pin 30. Located on one side of lever 33, see Fig. 4, is a pointer 48, it is pivotally attached to lever 33 by a bolt or pin 49, a shoulder bolt 50 is rigidly securable to said pointer by a nut. Said bolt 50 passes through an arc-shaped slightly elongated or slotted opening in lever 33 and on the opposite side of lever 33 is located a device designated as a notch finder 51. It is also pivotally mounted on bolt or pin 49, and bolt 50 also passes through it, and by means of a handle nut 52 the pointer 48 and notch finder 51 are both rigidly secured to lever 33. Notch finder 51 comprises a barrel piece into which is inserted a spring actuated taper nose plunger 53, said plunger engages in a limited number of V like notches cut in the under side of quadrant 34, or into a circle piece attached thereto.

The above stated V like notches are so disposed as to indicate the proper position of lever 33 in order to yield certain predetermined movements of the setting mechanism,

and inasmuch as pointer 48 and notch finder 51, are rigidly connected by bolt 50, irrespective of compression applied by handle nut 52, it is evident that by slackening handle nut 52 and withdrawing latch 35, lever 33 70 may be moved back and forth within certain limits and latched accordingly without disengaging plunger 53, or even changing the reading of pointer 48, thereby providing a limited adjustment of lever 33 75 which is instantaneous, as the adjustment can readily be made without tools while the carriage is in motion and the saw is passing through the log. Furthermore and inasmuch as the plunger 51 is free to yield, 80 and therefore does not act as a positive, but merely a limited or yielding obstruction to the movement of lever 33, the operator can readily determine by sound and touch alone, precisely when the plunger of said notch 85 finder registers with any one of the aforesaid V type notches, and as their number is quite limited he quickly learns just what position of lever 33 each V shaped notch indicates.

The operation of the device is very simple. All parts of the device are shown in what is termed a home position, and which permits of the setting lever 33 being moved to, and latched in any desired position on the 90 quadrant 34, and as its lower end has means of connection with sliding block 42, the latter is correspondingly moved to, and locked in, any desired position on the guide 38, carried by arm 37. In the position shown, 100 block 42 is so located as to bring pivotal bolt 43 directly in line with shaft 36 and while in this position, the rocking of arm 37 imparts little or no movement to bolt 43, link 47 or rocker shaft 20.

By moving valve lever 15 outward from valve chest 12, compressed vapor is admitted to the inner or stuffing box end of cylinder 8, and gradually liberated from its outer end, thereby forcing piston 9 and piston rod 10 inward, which, with the aid of link 40 causes arm 37 to rock forward. When piston 9 reaches the end of its stroke by contacting with the outer head of cylinder 8, the valve and piston movements are reversed, thus bringing all parts back to the home position from which they started. Thus far no movement has been imparted to the rocker arm 29, or rocker shaft 20 but by moving the setting lever away from its neutral or shown 110 position, block 42 is moved upward in guide 38 until pivotal bolt 43 is no longer in line with, but above shaft 36. By then repeating the valve and piston movements, pivotal bolt 43 describes a concentric oscillating movement, and by the aid of link 47 imparts a corresponding movement to crank 30 and rocker shaft 20. Said movement being wholly determined by the position of block 42 on guide 38, and which as stated is en- 125

tirely controlled by the position of the setting lever 33.

A circular dial 8^a is shown attached to cylinder 8, its purpose is to indicate the distance between standards 4 and the saw line, it, however, is not involved in my application.

I wish to place particular emphasis on my method of controlling the movement of piston 9 of my device, and in order to make same more clear I have deemed it proper to devote a section of the specification to said method exclusively as presented in Figs. 5 and 6, and in which the interior arrangement of all ports and steam chambers are clearly illustrated. Valve chest 12 preferably rests on top of cylinder 8. It is provided with a central steam inlet and chamber 54, and exhaust outlet 55, also exhaust chambers and ports 56 and 57, both of which lead to exhaust outlet 55. Leading from steam chamber 54 which is in the center of said valve chest, is a large steam port 58 which leads to the inner or stuffing box end of cylinder 8, and a similar port 59 leads to the outer end of said cylinder. Leading from a point some distance from the outer end of cylinder 8 is a small exhaust port 60 which terminates in exhaust chamber 57 of chest 12, and an exhaust port of like character 61 leads from a similar point in the inner end of said cylinder, and terminates in exhaust chamber 56 of said chest. Leading from steam port 58 to exhaust port 61 is a small port 62, and forming a like connection between steam port 59 and exhaust port 60 is a similar small port 63. Partially inserted in said small ports 62 and 63 respectively, are adjustable control plugs 64 and 65 and by means of which the active area of ports 62 and 63 may be precisely fixed. Exhaust ports 60 and 61 are drilled ports, therefore, the area of the entire exhaust outlet is accurately predetermined as well as subject to control. The position of valve 13 shows steam port 59 open and piston 9 resting against the inner head of cylinder 8 under full steam pressure. Steam port 58 being closed at its upper end by valve 13, and the upper terminal of exhaust port 61 being open to exhaust chamber 56. The lower end of steam ports 58 and 59 lie sufficiently near the extreme ends of cylinder 8 as to always preserve partial openings of their lower ends into cylinder 8. It will be observed therefore, that with valve 13 in the position shown, if piston 9 was just leaving the outer end of cylinder 8, the exhaust steam would not only flow out through exhaust port 61 until piston 9 reached and closed said port at its lower end, but that it would during said entire time, also flow out through steam port 58 by way of the small port 62 and upper end of exhaust port 61, also that said latter flow would be continued

until piston 9 had reached the position shown. Inasmuch as each end of cylinder 8 and valve chest 12 is provided with duplicate ports, it naturally follows that if valve 13 be moved to its opposite position in chest 12 a similar flow of steam and piston movement will take place. Furthermore as the in-flow of steam is unrestricted, while the outflow is closely restricted by two outlets of predetermined area, one of which remains open continuously throughout the entire stroke while the other is interrupted at a predetermined point, it is evident that the movement of the piston will be positive, strong and uniform at a fixed and predetermined speed up to the point where said outflow is interrupted, also that it will positively complete its stroke at a steady but lower rate of speed with no tendency to cushion or recoil. Fig. 7, illustrates a most popular method of cushioning a piston at or near the end of its stroke, and in which valve chest 12^a and valve 13^a are almost identical with those used in my device, omitting, however, the small cross ports 62 and 63.

In Fig. 7, however, the opening at the top of the valve becomes the steam inlet and chambers 56^a and 57^a become steam chambers instead of exhaust chambers, and opening and chamber 54^a becomes an exhaust chamber, a steam port 58^a leads from valve chest 12^a to the inner end of cylinder 8^a, a like port 59^a leading to the opposite end of said cylinder. Exhaust port 60^a leads from near the inner end of said cylinder to valve chest 12^a and a like port leads from near the outer end of said cylinder to said chest. Control pins or plugs 64^a and 65^a (when used) are located substantially as shown.

In devices of this character the functions performed are invariably of a character which do not require the piston to positively complete a definitely fixed stroke; neither is a cushioning and rebounding action objectionable.

The device shown by Fig. 7 illustrates valve 13^a in such position that steam is being admitted to the inner end of the cylinder through port 58^a and exhaust port 60^a is also open. When the piston 9 reaches port 60^a, however, and cuts off the out-flow of exhaust, it is cushioned by the imprisoned vapor, is apt to rebound, and does not immediately reach the end of the cylinder, but depends upon leakage or small bleeders (not shown) extending from the exhaust ports to the end of the cylinder to permit of its reaching the end of the cylinder. The method shown and thus described is frequently employed in devices having an otherwise violent or rapid piston movement, and even when control plugs 64^a and 65^a are added, it is usually done for the purpose of slightly diminishing the speed of the piston,

but the latter in no wise eliminates the cushioning effect when the exhaust ports are closed by the action of the piston in passing over them.

In my device, the steam in-flow is ample to maintain the boiler pressure at a piston speed of fully four times that of the actual piston speed employed, but as a free exhaust flow is not permitted, but is closely restricted, the piston is resisted by a back pressure so near equal to the supply pressure, that it is virtually steadied between two high pressures and is virtually moved by a very low mean effective pressure, in fact, so low that a change in back or exhaust pressure of even three or four pounds per inch, would reduce or increase said mean effective pressure at least 50%, thereby causing the piston to promptly respond to all logical changes in load resistance with no perceptible change in speed so long as the exhaust out-flow remained unchanged, while the very instant that the piston reaches the point at which a moderate portion of the exhaust out-flow is cut off, its speed will change and conform to that permitted by the remaining exhaust out-flow and without involving any perceptible cushioning effect whatsoever.

In a number of machines which I have already tested and put into service, I have demonstrated that the foregoing method of piston control produces a piston movement that has never been produced or even approximated in any other steam log setting device that has so far been brought to public attention, regardless of whether they employed single or multiple cylinders, or even air or oil control, and yet all of the factors which contribute to same are so difficult to define that the following information and explanation may be found advantageous.

Reciprocating piston, motor actuated set-works, may justly be divided into two classes. One in which the movements of the setting mechanism are varied by varying the stroke of the piston, while in the other the variation is effected by variable means between the piston and the usual setting mechanism, without changing the stroke of the piston. My device belongs to the latter class.

In each, however, and in order to obtain even a fair measure of accuracy, it is necessary for the piston to promptly and positively complete the maximum stroke which for the time being is allotted to it. No machine, however, employing a free exhaust throughout the greater part of the stroke, in connection with a piston cushioning system at the end of the stroke, has so far reached the public or been developed to a point where it accomplishes the aforesaid result without imparting enough inertia to members attached to the setting shaft and knees or standards, to carry them beyond the

true point indicated by the travel of the actuating parts of the motor, therefore their accuracy and effectiveness has been seriously impaired by what is termed over setting, or over throw.

In my device a free exhaust is at no time permitted, owing to the fact that the maximum exhaust is restricted to a point where a predetermined rate of piston speed of substantially 68' to 70' per minute is at no time exceeded, said speed being assumed promptly on the opening of the ports and being uniformly maintained until near the end of the stroke, where a slight reduction of piston speed is effected, in fact only sufficient reduction to bring all moving parts down to a speed slightly below that which I have found begins to show inertia of the setting shaft and knees, and which is not detectable in such devices, (having the usual intervening mechanism), until a piston speed of at least fifty feet per minute is exceeded. In my device, however, no cushioning effect is desired, attempted or effected but merely a moderate reduction of an already predetermined moderate speed. The piston movement prior to this being almost if not actually the same as in hydraulic devices. It must become evident to anyone skilled in the art, that a sudden stopping or even of checking up of actuating mechanism having sufficient speed to produce high inertia, will not effectively retard or control other moving members which are still free to move forward, this fact when considered in connection with the necessity for the piston to promptly finish its predetermined stroke, confronts the designer with a problem which is not found in the many steam using and cushioning devices, in which their natural function is successfully performed without requiring the piston to absolutely complete its entire stroke, or in fact to go little if any beyond the point where the cushioning effect begins. Another feature distinctly involved in my method of control, calls for additional explanation. Sawmill carriages usually employ 3 or more head blocks, 3 being the popular number. The standards of the popular sizes in large modern mills will approximately weight 500 lbs. each, or in all 1500 lbs. A log that will yield 300 ft. of lumber (which is far above the average) will weigh if hardwood about 2,700 lbs. making in all approximately 4,200 lbs.

To move said knees and log will require substantially 35% of said weight, or a force applied to the standards of 500 lbs. The ratio of the pinions to the point at which power is applied to the pawl carrier is approximately as 1 to 4 thereby requiring a force at this point of approximately, but 350 lbs. The travel of the pawl carriers at no time more than slightly exceeds that of

the piston, hence it will be seen that a piston energy of about 350 lbs. plus a slight addition for friction is all that is actually employed. Notwithstanding these facts, the cylinder of the motor in my device as now being built and successfully employed is 10" in diameter, and which under the working pressure now used in most mills, (approximately 100 lbs. to 110 lbs.) would if necessary yield a maximum piston energy of substantially 7,850 lbs.

From this it is seen that the energy employed under load conditions far above the average, is less than 5 per cent. of the maximum piston energy, or requires a mean effective pressure of not over 5 lbs. per inch, these facts considered in connection with an unrestricted steam inlet, and a closely restricted exhaust outlet, not only establishes the fact that the piston in my device is practically moved and controlled by a discrepancy of not exceeding 5 lbs. per inch, between that on the live steam side and that on the exhausting side of said piston, but also makes it clear that a variation of a pound or two in said discrepancy would be ample to meet any logical increase of load resistance, or to slow up the speed of the piston, depending of course on whether the pressure rose or fell said amount on the side of the piston which was exhausting.

It is therefore the conditions stated which not only render a cushion effect entirely unnecessary in my device, but which enables me to obtain a reduction of piston speed with so little rise in exhaust resistance at any point, that it is barely detectable with an indicator. My device as above constructed also demonstrates that after a supply pressure of 50 to 60 lbs. per inch is reached; (which seems to be ample to maintain boiler pressure in the cylinder through the steam ports provided, and at the piston speed stated) any increase or variation in pressure between said 50 to 60 lbs. and 150 lbs. makes no change in the piston movements, that is detectable by the eye, ear or count, irrespective of whether the piston and rocking link only are being moved, or whether the machine is operating under heavy load, and full stroke, of the setting mechanism, this fact I attribute to the further fact the steam pressure on both sides of the piston at all times remains within said 4 or 5 lbs. of being equal, for it is well known that a cubic foot of steam, regardless of its pressure will flow through a fixed orifice, in substantially the same time, if acted on continuously by a force equal to the former's initial pressure.

Still another distinguishing feature of my method of piston control as compared with other steam set works, is the fact that it is effected entirely without any action or movement of the valve during the stroke of the piston, since all restriction of the ex-

haust takes place before said exhaust steam reaches the valve chamber, and therefore is not affected by wear of the valve. I have found that in devices employing port arrangements similar to those shown in Fig. 7 with its cushion plug omitted and a free exhaust, that the exhaust pressure falls very low during the middle of the stroke, while at the termination of the stroke, it rises far above the initial pressure, the result being that as the valve and piston rings became worn the piston began to strike the cylinder head with considerable impact, also that when the piston rings and valve became badly worn, or the piston rings broken the piston was driven against the cylinder head with terrific impact all of which was due to the fact that the high terminal pressure drove a large portion of the otherwise imprisoned steam through the leak of the valve and also back by the piston into the live steam side of the cylinder also that when the piston movement was being but slightly curtailed by cushion plugs or regulators, said plugs had to be inserted farther as wear progressed.

While in my device, the removal of the piston rings entirely only causes the piston to slow down, and as the steam, which escapes by the piston to the exhausting side thereof also has to escape along with the previous contents of the cylinder through the aforesaid predetermined exhaust openings, it becomes necessary to slightly withdraw the exhaust regulating plugs, instead of further inserting them.

Now I do not claim the exclusive right to exhaust restriction, on to cushioning the piston at the end of its stroke under all conditions or the exclusive right to imparting motion from the piston to the rocker shaft of the setting mechanism by means involving an arm having a sliding block adjustably arranged thereon.

What I claim is:

1. A machine element adjusting mechanism comprising an intermittent grip device having a back and forth motion, a constant throw fluid pressure cylinder and piston motor, having the usual unrestricted inlet passages, and having exhaust passages constantly restricted sufficiently to materially reduce the piston speed below that which the fluid pressure would otherwise impart to it, in combination with means for transmitting the constant throw of the piston to the intermittent grip device, which means is adjustable to pre-determinedly vary the range of movement imparted thereby to said grip device.

2. A machine element adjusting mechanism comprising an intermittent grip device having a back and forth motion, a constant throw fluid pressure cylinder and piston motor, having the usual unrestricted in-

6
let passages and having exhaust passages sufficiently restricted to materially reduce the piston speed below that which the fluid pressure would otherwise impart to it, and 5 further restricted by the advance of the piston toward the end of the stroke, in combination with means for transmitting the constant throw of the piston to the intermittent grip device, which means is adjustable to pre-determinedly vary the range of 10 movement imparted thereby to said grip device.

3. A machine element adjusting mechanism comprising an intermittent grip device having a back and forth motion, a fluid pressure cylinder and piston motor having the usual unrestricted inlet passages and having exhaust passages restricted throughout the entire piston stroke irrespective of 20 any valve movement during said stroke, sufficiently to materially reduce the piston speed throughout said piston stroke, below that which the fluid pressure would otherwise impart to it, in combination with 25 means for transmitting motion from the piston to the intermittent grip device.

4. A machine element adjusting mechanism comprising an intermittent grip device having a back and forth motion and embodying a rocking actuating shaft, a crank pin having a crank arm rigidly secured to said shaft, an oscillating member supported at one end by a fixed pivotal support, an arc shaped guide formed by said oscillating 30 member and so set as to become concentric to said crank pin when at rest in idle or home position, a cylinder, fluid pressure motor, having a piston and piston rod working therein, a connecting rod leading direct 35 from said piston rod to the free end of said oscillating member for imparting motion thereto, an adjustable arc shaped member carried by the arc shaped guide on said oscillating member, means for adjusting said 40 adjustable arc shaped member upon said guide, and a link pivotally attached direct 45 to both said arc shaped adjustable member

and said crank pin, whereby a concentric guiding member having a uniform or fixed oscillatory movement and axis is actuated 50 directly by a rod extension of said motor's piston, and at the same time becomes a direct element in affording means for changing the relative movement of the intermittent grip device and the piston of said motor. 55

5. A machine element adjusting mechanism comprising an intermittent grip device, having a back and forth motion, a constant throw fluid pressure cylinder and piston motor, having inlet passages of ample size 60 to admit and maintain the full and unrestricted supply pressure upon the piston, and having exhaust passages constantly restricted sufficiently to materially reduce the piston speed below that which the fluid pressure would otherwise impart to it, in combination with means for transmitting the constant throw of the piston to the intermittent grip device, which means is adjustable to predeterminedly vary the range of movement imparted thereby to said grip device. 65

6. A machine element adjusting mechanism comprising an intermittent grip device, having a back and forth motion, a fluid pressure motor, having a cylinder, a piston, and a hand controlled valve for alternating the flow of fluid to and from said motor, and having inlet passages of ample size to admit and maintain the full and unrestricted supply pressure upon the piston, and having exhaust passages constantly so restricted throughout the entire piston stroke, that without any aid from additional or supplemental valves, the piston speed is materially reduced throughout its entire stroke below 75 that which the fluid pressure would otherwise impart to it, in combination with means for transmitting motion from said piston to 80 said intermittent grip device. 85
